UNITED STATES PATENT OFFICE

CASIMIRO HERNÁNDEZ SÓLÁ, OF BARCELONA, SPAIN

MACHINE FOR UNDULATING WIRE

Application filed December 23, 1927, Serial No. 242,239, and in Spain February 24, 1927.

This invention relates to machines for producing ornamental wire employed for weaving metal trellis work and the like.

Ornamental rectangular metal trellis work or mesh which is employed for fences and many other purposes is formed by a series of parallel wires which are interlaced with another series of wires of the same form arranged at right angles to the first.

10 These wires comprise a number of undulations which are repeated in each square and which are the ones forming the design. As it will be understood, these undulations are very varied in form. Moreover, as the 15 wires possess a certain thickness, they tend to ride over each other at the crossing points with the result that the resulting metal trellis work or fabric presents what may be called a defect, that is, it is not flat.

20 With the object of preventing this, the wires are undulated at the crossing points in a plane at right angles to that containing the ornamental undulations and thus a flat weave is obtained.

25 From this it is seen that in order to manufacture the said lattice work, after having obtained a straight wire of the desired section and thickness by known means, it is necessary to prepare it so as to form the 30 said undulations which, as will be understood from the foregoing are at right angles to each other. After this effect has been produced the wires are woven.

One machine which has been employed for 35 producing these sets of undulations in the wire consists in a double press into which the straight wire is inserted and in which one lever produces one undulation (the ornamental) and another lever which works at 40 right angles to the first the other undulations (at the crossing points), and in this way the said wire is passed through the machine and undulated. Such a machine occupies a considerable amount of space.

45 Another machine employed for the purpose, which is more rapid, consists in a pair of rollers or discs in which are set a series of projections so as to resemble a pair of toothed wheels, between which rollers or 50 discs the wire is passed and thereby undu-

lated in one single direction; and after this the other series of undulations is produced in a separate press.

Although this method is much more rapid than the preceding one it presents the defect 55 that it is difficult, when forming the second series of undulations, to preserve accurately the required distance between the first undulations and the second, so that upon weaving the crossed wires are out of centre.

In a machine for producing such ornamental wire work it has also been proposed to employ four double faced bevel wheels formed with dies or moulds circumferentially around their peripheries, designed, when 60 in operation, to meet in a common effective point, one pair of co-operative wheels being in a horizontal plane and the other pair in a vertical plane. The wire is passed between the wheels at the common effective point so that one pair of wheels undulates it in one 65 plane at the same time as the other undulates it in a second plane at right angles to the first.

The object of the invention is to provide 70 a machine for producing such undulations in wire in two planes situated at an angle to each other, and the machine according to 75 the invention comprises, in a unitary construction, a first pair of co-operating rotatable discs or the like arranged in one plane, between which the wire passes so as to form the undulation in this plane, and a second pair of such discs, separate from the first, arranged in the second plane, between which 80 the wire passes after leaving the first pair, so as to form the undulations in the second plane.

In the accompanying drawings, Figs. 1, 2 and 7 show respectively an end elevation, 85 side elevation and plan view of an embodiment of the machine according to the invention.

Figs. 3 and 5 show two designs of ornamental wirework of the type described.

Figs. 4 and 6 show the undulations in the wires forming the trellis work in Figs. 3 and 5 respectively.

Figs. 8 and 9 are details of the machine 95 illustrated.

In Figs. 3 and 5 X—X and Y—Y are the two series of parallel wires which are interlaced to form the trellis work while in Figs. 4 and 6, a—a are the ornamental undulations and b—b are the undulations at the crossing points for producing a flat weave.

The machine illustrated in Figs. 1, 2 and 7 comprises two pairs of discs, rollers or cylinders A—B, C—D. The rollers A and B have parallel axes and are situated in a vertical plane, the rollers C and D also have parallel axes and are arranged in a horizontal plane. The rollers A and B engage and the rollers C and D also engage and are arranged in such a way that the wire, leaving the rollers A—B is caught by the rollers C and D. That which has been called "engaging" is not an engagement in the mechanical sense of the word. It is here simply intended to mean that upon the said discs (or rollers) are set a series of teeth in such a way that a projection of A or C corresponds with a recess on B or D respectively, and that sufficient space is left between them for the passage of the wire which is thus undulated.

In Figs. 8 and 9 a part of these rollers is shown in detail. They are of cast iron machine turned, and upon their peripheries are set the projections or teeth a', b', c, d which are members of suitable form made of tempered steel and spaced the required distances apart.

From a consideration of the machine and of its work, it will be seen that the applicant has designed the former so that it will produce this desired effect of preventing the interposed series of undulations from advancing relatively to the others. For this purpose the main or driving shaft E which receives the power, is arranged to drive by means of a worm, the worm wheel F upon the shaft of which is mounted the cylinder or disc B; by means of the similar toothed wheels H and J, its movement is transmitted to the shaft K, upon which is mounted the disc A which co-operates with the disc B, and by means of the system of helical wheels L and M drives the shaft N which through another helical system O—P drives the shaft Q upon which is mounted the disc D and also the spur wheel R which engages with another wheel S similar to itself upon the shaft T of which is mounted the disc C.

In this way the same distance is preserved between each consecutive pair of undulations.

The whole arrangement is mounted upon a rigid bed U, one form of which is indicated in the figures, upon which are mounted the bearing and supports for these transmissions and discs.

It will be understood that modifications may be made in the constructional details

without on that account going outside the scope of the invention.

What I claim is:

1. A machine for producing ornamental undulations in wire in two planes, situated at an angle to each other, comprising, in a unitary construction, a first pair of co-operating rotatable discs or the like arranged in one plane, between which the wire passes so as to form the undulation in this plane, and a second pair of such discs, separate from the first, arranged in the second plane, between which the wire passes after leaving the first pair, so as to form the undulations in the second plane, shafts carrying discs, and means mounting the shafts on one side only of each pair of discs.

2. A machine as claimed in claim 1, characterized by the provision of a drive shaft connected with one of the discs of the first mentioned pair, and a driving connection between said shaft and one of the shafts of the discs of the second pair.

In testimony whereof I have signed my name to this specification.
